UNITED STATES PATENT OFFICE.

ANDERS JOHAN E: SON MUNTERS, OF STOCKHOLM, SWEDEN, ASSIGNOR TO STARTING KOMPANIET FÄRERAUS, HULT & CO., OF STOCKHOLM, SWEDEN.

STARTING DEVICE FOR INTERNAL-COMBUSTION ENGINES.

Application filed July 9, 1920. Serial No. 394,911.

To all whom it may concern:

Be it known that I, ANDERS JOHAN E: SON MUNTERS, a subject of the King of Sweden, residing at Luntmakaregatan 7, Stockholm, Sweden, have invented certain new and useful Improvements in Starting Devices for Internal-Combustion Engines, of which the following is a specification.

This invention relates to starting devices for internal combustion engines of the type in which the starting handle or its shaft is directly or indirectly connected, on the one hand, with the engine shaft by a clutch disconnectible, by the reverse of the engine, but not by a normal resistance exerted on the handle, and, on the other hand, with a stationary member by the aid of a lock adapted to operate in one direction only.

The object of such a device is to prevent the starting handle from partaking in the backwards running of the engine shaft, should the engine be inadvertently reversed while starting. Although this object has been attained; inasmuch as the handle is disconnected from the engine shaft in case of backward running, experience has however proved that disconnection does not take place, until the handle has turned through an angle of such a magnitude as to be dangerous to the operator, and owing to the fact that a backwards running may be measured only in thousandths of a second, the above mentioned backward running of the handle, though performed through a few degrees, may give rise to accidents.

The object of this invention is to prevent any backward running of the handle, in case the engine should be reversed. The part of the device being of the greatest importance is the lock device located between the above mentioned stationary member and the handle or its shaft. Said lock device must be constructed so as not to allow lost motion or play, until the locking members are in full mutual engagement, since otherwise said motion will be transferred to the handle, and as the peripheral speed of the latter is considerably greater at the grip than

at the centre, where the locking members are located, the movement of the handle will, as mentioned above, be dangerous.

In order to prevent lost motion or play in the locking device, the latter consists according to the invention of a friction-roller or ball-lock or any other similar one way locking device. The device will consequently be instantly operative at the beginning of the backward running, while locking the handle at once when operating in the forward direction.

Three embodiments of the invention are illustrated in the accompanying drawing, in which—

Figures 1 and 2 are a central sectional view and an end view respectively of one embodiment.

Figure 3 is a sectional view of the second embodiment and

Figure 4 is a similar view of the third embodiment.

In the drawing, 1 designates the starting handle, 2 a member entrained by the handle and 3 a stationary member. Disposed between the members 3 and 2 is a lock, as for instance a common roller-or ball-lock 4 in such manner that the member 2, without being prevented by the lock, may be entrained by the handle and the shaft in the forward, but not the backward direction. Extending from or engaging the member 2 or any member or members connected therewith is a clutch consisting, as shown in Figures 1, 3 and 4, of buffers 5 actuated by coiled springs 6.

In the embodiment shown in Figure 1 the springs 6 are inserted in a socket 7 secured to the engine shaft 8, said springs keeping the buffers 5 in contact with the member 2. Said member is provided with recesses corresponding to the conical outer surfaces of the buffers. The handle 1 (Figure 1) is, as usual, provided with recesses or notches co-operating with pins 9 or other catchers disposed on member 2. If the engine starts in the proper direction, the handle is disconnected axially as usual. If

the engine, on the contrary, runs backwards, the member 2 is locked, and as the handle is in engagement with said member, no movement of the handle, neither backwards nor axially, takes place, the clutch 5, 6 being disconnected and allowing backwards running of the engine shaft 8 independent of the handle.

The nut 10 is secured to the member 2, 10 for the purpose of keeping together the stationary member 3 and the clutch members inserted between the members 2 and 3. The nut may, however, also be so arranged as to serve as a catcher instead of the pins 15 9 when starting.

In the embodiment shown in Figure 3 adapted for automobiles or the like the principal parts of the device are similar to those shown in Figure 1 but are otherwise arranged. 1 is the handle, 2 the member entrained by the same, 3 the stationary member between which and the member 2 the lock 4 operating in one direction only is disposed. The handle 1 is by means of lugs 9¹ 25 in engagement with member 2. Located in the hub of the handle serving in this case as one part of the resilient clutch are the buffer springs 6 actuating the buffers, the conical portions of which engage the socket 7 secured to the starting shaft 8. This shaft forms an extension of the engine shaft and is by means of the clutch socket 11 connected with the corresponding socket of the latter shaft.

35 When starting the engine the shaft 8 and the handle 1 are disconnected as usual. On backward running the shaft 8 and the socket 7 are rotated, and the shaft will be disconnected from the buffers located in the hub of 40 the handle. The handle engaging the member 2 remains at a standstill.

Figure 4 illustrates a modification of the device shown in Figure 3. The handle 1 is secured to the shaft 8 and is by means of 45 lugs 9¹ on the hub of the handle connected with member 2. The shaft 8 is provided with a separate socket 7 secured to the shaft by the pin 12 and connected by the discon- 50 nectible clutch 5, 6 with the clutch socket 11. The latter is not movable axially but rotates on the shaft, while overcoming the resistance of the clutch 5, 6, should the engine run backwards when the handle remains at a standstill owing to the socket 7 being secured to the shaft 8 to which the handle is 55 attached, the latter being rigidly secured by means of the lugs 9¹ to the locked member 2.

In all the embodiments described above there may be used several clutches resilient 60 on account of an overload as well as pins, the strength of which are so adjusted as to allow breaking of the pins on backwards running.

The entrained member 2 may, as shown in 65 Figures 3 and 4, consist of the shaft 8; in

which case, however, the stationary member 3 should be immovable axially on said shaft. If the member 2 is connected with the shaft 8 by means of key and keyway, the shaft may move in the member 2; in which case 70 the member 3 need not be movable axially. 13 is the support of the shaft 8 bolted as usual to the engine frame.

All the embodiments described above are based on the arrangement of a member rotating with the handle at the starting, but locked upon backward running to a stationary member by means of an immediately acting locking device and thus serving as a firm resistance against the power requisite 75 for the disconnection of the resilient clutch from the engine shaft or any member connected with the same.

What I claim as new and desire to secure by Letters Patent of the United States is:— 85

1. A starting apparatus for engines including a part fixed to the engine shaft, a starting crank, a part rotating with the starting crank, spring-actuated detents arranged between these two parts and engaging in notches or recesses in one part, while they are displaceable in recesses in the other part, said recesses being arranged parallel with the engine shaft, coil springs enclosed in recesses and actuating the detents, a second fixed part surrounding the part entrained by the crank, and rolling lock-members arranged between the last-mentioned part and the second fixed part. 90

2. A starting apparatus for engines consisting of a part attached to the engine shaft, a starting crank, a part entrained by or rotating with the starting crank, spring actuated detents situated between these two parts, a fixed part surrounding the part entrained by the crank, rolling lock-members arranged between the last-mentioned part and the fixed part, an outer track for the said rolling lock-members which is circular and concentric with the center of rotation of the crank, and an inner track for the said lock-members, said last-mentioned track forming a polygon, and one of the rolling members bearing against either side of the polygon. 100

3. A starting device for internal combustion engines, including a shaft, a starting crank, a member rigidly connected with the shaft, another member adapted to rotate relatively to said shaft and movable with the starting crank, detents arranged between said members and so devised that the same are normally in engagement with both members, resilient means for forcing the detents towards one of said members for normally maintaining the members in locked relation, one of said members, on the motor being reversed, being automatically disengageable from the other member and capable of overcoming the action of the resilient means, a 110

fixed part, a roller element lock arranged between said part and the member which rotates relatively to the shaft and adapted to immediately lock the last mentioned member when reverse movement of the engine takes place, and coil springs arranged in recesses in the member which is rigidly connected with the shaft for moving the detents

in one direction, said recesses being arranged parallel with said shaft. 10

In testimony whereof I affix my signature in presence of two witnesses.
